UNITED STATES PATENT OFFICE.

HENRY J. CHILTON, OF CHICAGO, ILLINOIS.

BOTTLE-WASHING APPARATUS.

1,074,836.

Specification of Letters Patent.

Patented Oct. 7, 1913.

Application filed July 25, 1910. Serial No. 573,737.

To all whom it may concern:

Be it known that I, HENRY J. CHILTON, a citizen of the United States, residing at the city of Chicago, county of Cook, and State of Illinois, have invented certain new and useful Improvements in Bottle-Washing Apparatus, of which the following is a specification.

This invention relates to improvements in bottle washing apparatus and refers more particularly to a rotary washing machine for cleansing milk bottles and the like.

Among the salient objects of the invention are to provide a construction in which a plurality of bottles are carried by a rotary main frame and a series of washing operations automatically performed upon the bottles; to provide a construction in which the bottles are automatically lowered into and raised out of a tank of water and while so lowered washed both interiorly and exteriorly; to provide a construction in which the exteriors of the bottles are automatically rinsed during their travel after they have been subjected to the aforesaid washing operations; to provide a construction in which the bottles are automatically shifted into and out of alignment with the washing and rinsing apparatus at predetermined intervals and in which the bottles are also so shifted as to permit the operator to readily remove or replace them in the bottle holders; to provide a construction in which the bottles are soaked during the entire washing operation and during their travel around the machine; to provide in a construction of the character referred to mechanism for more effectively washing the interior of the bottles; to provide a construction in which the exteriors of the bottles, after being washed are first rinsed with hot water and then sterilized by steam; to provide simple and improved compensating mechanism for washing bottles of different or unequal sizes; to provide means for permitting the air in the bottles to escape when their interiors are being washed in order that the water may more readily enter the bottles; to provide in a construction of the above character means for automatically cooling the bottles after they have been subjected to the washing and rinsing operations in order that they may be more readily removed by the operator; to provide simple and improved means for automatically performing the washing and

rinsing operations; to provide in a construction of the above character improved means for automatically performing the washing and rinsing operations; to provide in a construction of the above character improved means for automatically spinning the bottles while the latter are being washed, and in general to provide an improved construction of the character referred to.

The invention consists in the matters hereinafter described and more particularly pointed out in the appended claims.

In the drawings—Figure 1 is a vertical sectional view of the machine. Fig. 2 is a top plan view with parts broken away and shown in section. Fig. 3 is an enlarged fragmentary vertical sectional view taken on lines 3, 3 of Fig. 1 and looking in the direction of the arrows. Fig. 4 is a similar view, the bottles however being shown as lowered into the tank. Fig. 5 is a fragmentary vertical sectional view showing certain details of the washing apparatus and taken at substantially right angles to the view shown in Fig. 4. Fig. 6 is a sectional detail of one of the brush spindles. Fig. 7 is a sectional view taken on lines 7, 7 of Fig. 1 and looking in the direction of the arrows. Fig. 8 is a detail view showing the manner of supporting one of the rock shafts which carries the bottle holders. Fig. 9 is a fragmentary horizontal section taken on lines 9, 9 of Fig. 5 and looking in the direction of the arrows. Fig. 10 is a fragmentary sectional view taken on lines 10, 10 of Fig. 5 and looking in the direction of the arrows. Fig. 11 is a detail view showing the manner of supplying water to the rinsers. Fig. 12 is a detail view of another portion of the same mechanism and showing more particularly the parts controlling the supply of water to the rinsers. Fig. 13 is a fragmentary sectional view taken on lines 13, 13 of Fig. 5 and looking in the direction of the arrows.

Referring to the drawings, 1 designates the base casting of the machine at either side of which is supported a pair of standards 2 which carry an upper frame casting designated as a whole 3. Between these castings is mounted a rotary main frame 4. This main frame consists essentially of a base support 5 carrying a water tank 6, and a hollow upright or post 7, and an upper circular casting 8. The latter is bolted to the upper end of the post 7 as

shown at 9, 9. The post is also preferably secured to the base of the rotary main frame by means of screw bolts 10.

Water is supplied to the tank 6 by means 5 of a main supply pipe 11 and an extension 11' which extends into the hollow upright 7. This pipe is controlled by a suitable valve 12. In order that the water may pass from the central upright 7 into the tank, 10 the former is apertured at its lower end as shown at 13. The tank is provided with an over-flow pipe 14. Within the tank are mounted a plurality of brush spindles 15 carrying brushes 16. The lower ends of 15 these spindles are rotatably journaled in suitable sockets 17 in the bottom of the tank while the upper ends of the spindles are similarly journaled in sockets 18 carried by the upper casting 8 of the rotary main frame.

Referring now to the bottle holders, upon the upper edge of the tank is mounted a series of journal brackets or trunnions 19 which carry posts 20. These posts extend 25 to the upper end of the machine and are journaled as shown at 21 in the casting 8. Upon each of these posts is slidably mounted a sleeve 22. Each sleeve is secured to its post by a feather 23 which prevents the 30 rotation of the sleeve independent of the post but permits it to slide vertically thereon. Upon each of the sleeves 22 is loosely mounted a bracket 24 having a sleeve like extension 25 telescoping over the inner 35 sleeve 22. The bracket 24 is provided at its upper end with a counter bored extension 26 in which is seated a compression spring 27, the upper end of which bears against a collar 28 threaded to the inner sleeve 22. To each 40 sleeve 25 is secured a supporting bracket 29 by means of a split collar 30 and through bolt 31. These brackets 29 are provided with bosses 32 extending over the brush spindles 15. Between the boss and the 45 spindle is mounted a gear 33 which is splined to the spindle by means of a feather 34 in such a way as to permit the boss and gear sliding vertically on the spindle. As shown at 35, the gear is provided with a 50 sleeve screw-threaded to the lower end of the boss. Each of these brackets is also provided with two bosses 36 in which are mounted the spindles 37 of the spinners 38. Each of these spinners 38 is adapted to fit 55 over the upper end of an inverted bottle and both center and spin the same in a manner hereinafter described. The upper end of each spindle 37 is keyed, as shown at 39, to a pinion 40 which meshes with an idler gear 41 journaled on a stud 42 seated in the upper end of the bracket 29. These idler 60 pinions 41 are driven by the gears 33, here- 65 tofore described, upon the rotation of the brush spindles 15. Upon the lower end of each inner sleeve 22 are swaged or otherwise

fixed bottle holders 43, there being four of these holders for each sleeve.

The spinning and centering devices are so arranged as to compensate for any small inequalities in the size of the bottles. To this end each bracket 29 is provided with an angle stud 44 on which is pivoted an equalizer 45. The arms 45' of this equalizer engage the upper end of the spinner spindles 37 and allow for a differential movement therein 70 so as to insure of the spinners always being in engagement with the bottles. 75

The brackets 29 may be adjusted vertically upon the posts 20 by loosening the bolts 31. This permits of the spinners being raised or lowered to accommodate the various sizes of bottles. In this connection it will be noted that the gears 33 are so splined to the brush spindles 15 as to have limited vertical movement thereon when the 80 brackets 29 are adjusted. 85

Referring now to the manner of raising and lowering the bottle holders, each of the brackets 24 is provided with a boss 46 in which is journaled a cam roller 47 riding on a cam track 48 which extends entirely around the machine. This cam track 48 is carried by arms 52 secured as shown to the upper stationary casting 3. As shown more clearly in Figs. 1 and 3 this cam track 90 is provided with a flat portion *a* and inclined portions *b* and *c* respectively. When the cam rollers ride down the incline *c* the bottle holders are shifted bodily downwardly and remain there while the rollers are passing over the portion *a* of the track. At this time the inner bottle holders extend into the tank while the corresponding outer pair of holders extend down over the rinsers in a manner hereinafter described. In order that the 100 sleeves 22 and 25 may extend down into the tank these sleeves are slotted at either side as shown at 48'. 105

While the bottles are in the tank they are subjected to both interior and exterior washing. The brush spindles 15 heretofore described are provided at their upper ends with pinions 49 which mesh with a circular stationary gear 50 rigidly secured by means of bolts 51 to the upper casting 3. As the 110 main frame turns around, the spindles 15 will obviously be rotated thus brushing the exterior of the bottles. The rotation of the spindles 15 also will spin the bottles in the opposite direction through the action of the 115 train of gears 33, 41 and 40. 120

At the same time that the exteriors of the bottles are being brushed as just described, the interiors of the bottles are being cleaned by means of inner brushes 54 mounted on 125 hollow spindles 55. These spindles 55 are keyed to a bushing 56, the lower end of which extends through a second bushing 57 seated in the bottom of the tank. The lower end of the bushing 57 is screw threaded as 130

shown at 58 and is fixed to the tank by means of a nut 59. In order to prevent leakage, a packing nut 60 is screw threaded to the lower end of the outer bushing 57, and between the end of the bushing and the inner face of the nut is seated a packing 61. The lower end of the inner bushing 56 extends through the outer bushing and is provided with a pinion 62 keyed to the bushing as shown at 63. These pinions 62 are driven from a common circular gear 64. This gear 64 is provided with a hub 65 journaled on a shoulder 66 carried by the lower main casting 1. On the lower end of this gear 64 is secured a circular beveled gear 67 which is driven from a pinion 68 carried by the main shaft 69. The latter is journaled in suitable bearings 70 carried by the base casting 1 and is driven from a pulley 71.

The inner brushing spindles 55 are provided with spiral blades 72' in order to more thoroughly agitate the water while the interior of the bottles is being washed. The upper ends of the hollow spindles 55 extend above the water line in the tank and inasmuch as these spindles are open at either end, the air in the bottles escapes through the spindles 55, thus permitting water to readily enter the bottles.

To insure of the brushes readily entering the neck of the bottles, I provide a series of posts 72 provided with a reduced threaded extension 74 which is threaded into the base of the rotary main frame. Upon each of these posts 73 is slidably mounted a bracket 75. Each of these brackets 75 carries a pair of annular bosses 76, in each of which is loosely mounted a sleeve 77 which telescopes over the corresponding inner brushes 54. The brackets 75 are connected to the sleeves 22 in such a way that the sleeves support the brackets but at the same time are free to rotate independent of the brackets. Accordingly the lower end of each sleeve 22 is provided with a flange 78 which rides in a forked arm 79.

Referring now to the manner of rinsing the interior of the bottles, in the lower end of the rotary main frame is screw threaded a bolt 80 which supports an annular casting 81. This casting is held in yieldable engagement with the lower end of the water tank by means of a coil spring 82 inserted between the base of the casting and the head 83 of the bolt. This casting is provided in its upper end with a pair of segmental chambers 84 and 85 respectively. From each of these chambers a plurality of ducts 86 lead to the outer edge of the rotary frame and terminate in forked extensions 87 which communicate with vertical rinser pipes 88 seated in the outer edge of the frame. Hot water is delivered to the chamber 85 by means of a delivery pipe 89 and similarly steam is delivered to the chamber 84 by

means of a pipe 90. The main frame is so rotated that the interiors of the bottles will first be rinsed with hot water and then sterilized with steam. This sterilization is particularly important in cleansing milk bottles and the like.

Inasmuch as each set of bottle holders carries four bottles, means are provided for alternately shifting the respective pairs of each set into and out of alignment with the rinsers after the bottles have been washed. To this end the stationary casting 8 is rounded at its outer edge to form a cam track 91 which extends entirely around the machine and is provided with a cam groove 92 portion 92. Opposite the cam portion 92 of the track is mounted a peculiarly shaped block 92'. Upon the upper end of each post 26 is fixed a forked arm 93 carrying a pair of cam rollers 94.

As the main frame rotates the cam rollers 94 engage the track 91 and prevent rotation of the posts. When, however, the cam rollers reach the cam portion of the track they engage the pointed extension 92" of the block 92' and the posts are rotated so as to reverse the position of the bottle holders. The arrangement is such that each pair of bottles, during one rotation of the machine, are in alignment with the washing apparatus and during the succeeding rotation of the machine are shifted into alignment with the rinsers. In view of the fact that the rinsers are on the outside of the washing chamber the bottles can be more readily removed and replaced by the operator.

As heretofore stated the exteriors of the bottles are also rinsed after they have been washed. To this end upon the stationary main frame are secured a pair of segmental water chambers 95 and 96 respectively. The bottom of each of these chambers is provided with a plurality of apertures or jet openings 97 in order that the water may spray over the upper ends of the inverted bottles. Hot water is supplied to the chamber 95 from the pipe 98 leading from a source of supply, and similarly cold water is supplied to the chamber 96. The cold water, by rinsing the bottles with cold water, temporarily cool them in order that they may not be too hot to be readily removed by the operator.

Describing now the manner of rotating the main frame and associated mechanism, in a journal bracket 99 is mounted a shaft, one end of which carries a beveled pinion 100 which drives a circular gear 101 secured to the lower end of the main frame and extending around the latter. The outer end of this counter shaft is provided with a gear 102 which is driven from a similar gear 103 carried by the main driving shaft 69. The arrangement is such that the main frame is rotated at a relatively low speed.

The water from the rinsers falls down onto the base of the stationary frame and passes into a pocket 104 from which it is drawn by means of a pipe 105.

5. The operation of the machine is apparent from the foregoing description. It will be noted, however, that when the machine is first started, only the one pair of bottles is inserted in each of the sets of holders and these automatically lowered into the tank and washed and soaked. When the bottle holders are raised out of the tank the operator fills the other pairs of bottle holders and the positions of the bottles are reversed.
10. Accordingly the bottles which have been washed are now rinsed while the other pairs of bottles are being washed. The arrangement is such that the machine can be run continuously and a much greater number of bottles both washed and rinsed than is possible in any of the present types of washing machines now in use.

The invention is not limited to the details of construction shown, except as set forth

25 in the appended claims.

I claim as my invention:

1. A bottle washing machine, the combination of a rotary main frame, a tank carried thereby, bottle holders adapted to be lowered into and raised out of said tank, and means for washing the bottles while in said tank.
2. In a bottle washing apparatus, the combination with a rotary main frame, of a water tank, a pair of bottle holders, means for alternately lowering each bottle holder into the tank, and means for washing the bottles when the latter are in said tank.

3. In a bottle washing apparatus, the combination with a main frame, of a tank, a plurality of bottle holders, means for lowering the bottle holders into said tank, brushes seated in said tank for washing the bottles, a plurality of rinsers extending around the tank, and means for raising the bottles out of the tank and for shifting them laterally with said rinsers.

4. In a bottle washing machine, the combination with a bottle holder adapted to hold a bottle in inverted position, a water tank, means for lowering the bottle holder into said tank, a brush for washing the interior of the bottle while in the tank, and means for permitting the air in the bottle to escape when the bottle is lowered into the tank.

5. In a bottle washing machine, the combination with a water tank, of a bottle holder for carrying a bottle in inverted position, reciprocal mechanism for lowering the bottle holder into the tank, a brush for washing the interior of the bottle, an open ended spindle for said brush, said spindle extending below the tank whereby

the air in the bottle can escape when the interior of the bottle is being washed.

6. In a bottle washing machine, the combination with a rotary main frame, of a water tank, a plurality of bottle holders rotating with said frame, reciprocal mechanism for lowering the bottles into and raising them out of the tank, means for washing the interior of the bottles while in the tank, and means for permitting the air to escape from the bottles when lowered into the tank.

7. In a bottle washing machine, the combination with a pair of bottle holders, of a pair of spinners co-operating with said holders for rotating the bottles, and a pivotally mounted equalizer bar for maintaining the spinners in uniform engagement with the bottles.

8. In a bottle washing apparatus, the combination with a rotary main frame, of a plurality of bottle holders rotating therewith, rinsing mechanism off-set from the normal path of movement of the holders, and means for rotatably shifting the bottle holders into and out of alignment with said rinsing mechanism.

9. In a bottle washing apparatus, the combination with a continuously rotating main frame, bottle holders traveling therewith, mechanism for rinsing the interior of the bottles normally out of the path of movement of the bottle holders, and means for automatically shifting said holders into and out of alignment with said rinsing mechanism.

10. In a bottle washing apparatus, the combination with a rotary main frame, of a series of bottle holders traveling therewith, mechanism for rinsing the exterior of the bottles normally out of the path of movement of said holders, and means for laterally shifting said holders into and out of alignment with said rinsing mechanism.

11. In a bottle washing apparatus, the combination with a rotary main frame, of a plurality of bottle holders traveling therewith, rinsing mechanism arranged out of the normal path of movement of said holders, and cam actuated mechanism for automatically shifting the bottle holders into and out of alignment with said rinsing mechanism at predetermined intervals.

12. In a bottle washing apparatus, the combination with a rotary main frame, of a plurality of bottle holders traveling therewith, a water tank carried by said frame, means for lowering the bottle holders into and raising them out of the tank, a plurality of spinners for said holders, a plurality of rotating brushes for washing the exterior and interior of the bottles, means for rinsing the bottles, means for permitting the air to escape from the bottles when the latter are

lowered into the tank, and means for operating said parts in properly timed relation.

13. In a bottle washing apparatus, the combination with a rotary main frame, of 5 a plurality of sets of bottle holders, each set holding four bottles, washing mechanism, rinsing mechanism, and means for shifting the bottle holders so that one pair of bottles of each set are alternately in alinement with 10 the washing and rinsing mechanisms and means for operating said parts in properly timed relation.

14. In a bottle washing apparatus, the combination with a bottle holder, of a tank, mechanism for lowering the holder into the 15 tank, a brush for washing the interior of the bottle in the tank, an air conduit extending into the bottle when the latter is lowered into the tank, to permit the air to escape from the bottle.

HENRY J. CHILTON.
